UNITED STATES PATENT OFFICE

JOSEPH JOHN NELIS, OF BROOKLYN, NEW YORK, ASSIGNOR TO FOSTER WHEELER CORPORATION, OF NEW YORK, N. Y., A CORPORATION OF NEW YORK

SUPERHEATER BOILER

Application filed April 26, 1926. Serial No. 104,538.

The general object of my present invention is to provide an improved superheater boiler. More specifically the object of my invention is to combine a radiant heat superheater with the combustion chamber of a boiler furnace in a novel manner whereby I obtain important practical advantages not obtainable with prior combinations. My invention is primarily characterized by the location of the superheater at the bottom of the combustion chamber of the boiler furnace, and in its preferred form the superheater elements form a sectional metallic floor for the combustion chamber. The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is a sectional elevation;

Fig. 2 is a partial section on the line 2—2 of Fig. 1; and

Fig. 3 is a partial section on the line 3—3 of Fig. 1;

In the drawings I have illustrated the use of my invention in a superheater boiler A, having a combustion chamber B, from which the heating gases pass upward into the inter-tube space of a bank of so-called horizontal tubes C. The latter are connected between a lower front header D and an upper rear header D'. Above the front header D, and connected to the latter is a steam and water drum E which is also connected to the header D' by circulator tubes C'. Suitable baffles F prolong the path of flow of the heating gases through the inter-tube space from the combustion chamber B to the heating gas outlet A' of the boiler. In the particular construction illustrated the outlet A' opens into an economizer G mounted on the top of the boiler proper. The boiler shown is designed

to be heated by the combustion of fuel burned in suspension in the chamber B, and injected into the latter through one or more burner inlets A² in a vertical wall of the chamber by a suitable fuel injector or burner H associated with each inlet A². As indicated in the drawing, the burner H is an oil burner.

In so far as already described, the boiler shown contains nothing peculiar to the present invention, but on the contrary is a marine boiler of well known type. While the present invention may advantageously be employed in boilers of very different type from that illustrated, the invention, for reasons hereinafter set forth, is of especial utility in the case of marine boilers, and possesses especial advantages in the case of a boiler heated by the combustion of fuel as oil or gas which is injected into, and is burned in suspension in the combustion chamber of the boiler.

In accordance with the present invention a radiant heat superheater is incorporated in the floor of the combustion chamber B. This superheater is formed by horizontally disposed tubular elements I which advantageously have thick walls of wrought steel, and are rectangular in cross section and are arranged alongside of one another so that they form a sectional metallic paving or plank-like floor for the combustion chamber. The elements I are supported, and held against objectionable deformation as a result of thermal expansion and contraction by means shown as comprising composite metallic floor beams K. Each beam K has a vertical web portion straddled by a corresponding pair of lugs I' welded to the underside of each element I, and connected to said web portion by a clevis pin J. As shown, the elements I extend between the side walls of the chamber B, and there are three beams K, one adjacent each side wall, and one at the center of the boiler. Bodily elongation and contraction of the elements I is accommodated by spacing the lugs I' of each pair apart by a distance greater than the thickness of the portion of the beam K between them. Advantageously, each

element is anchored at one point against movement in the direction of its length. This result is obtained, as shown, by means of washers O on one of the clevis pins J associated with each element, these washers filling the space between the corresponding lugs I' not filled by the corresponding beam K. Portions K' of the beams K support a metallic sheathing M beneath the elements I. Kieselguhr, an elastic refractory cement, or other heat insulating and gas leakage preventing material N, is interposed between the elements I and the sheathing M.

As shown, each element I is connected at its opposite ends to headers Q and R. The connection shown between each element I and the header Q comprises a nipple or thin walled tube *i* expanded or otherwise connected at one end to the corresponding end 20 of the element, and in alignment with the latter, and connected at its other end which extends through the side wall of the chamber B to a vertically disposed tube P, the connections being made by means of a connecting box P'. The upper ends of the tubes P are expanded or otherwise secured into the header Q. Each element I may be connected in the same manner to the header R, but as shown, the elements I are directly 30 connected to the header R by corresponding tubes *i* passing through the side wall of the chamber B. With the connections described, the elements I are preferably anchored, as shown, to the beam K nearest to the header R, so that the bulk of the bodily longitudinal expansion and contraction of the elements I may be accommodated by the transverse tubes P which are sufficiently flexible for the purpose. The side walls of 40 the chamber B may be formed of masonry or any other suitable material for the most part, but at the level of the superheater cast metal parts S are advantageously incorporated in the side walls to provide channels 45 loosely receiving the tubes *i*, and also receiving a yielding heat insulating and gas leakage preventing material T packed about the tubes *i*. The material T may be similar to the material N. The material T is 50 held in place at the outer ends of the channels by cover plates T', and at the inner sides of the furnace walls the material is held in place by the ends of the elements I, the supporting structure for the latter, and, 55 as shown, refractory material U covering the ends of the elements I.

As shown, the header Q receives steam at one end from the header E through the steam pipe E', and the superheated steam 60 is discharge through the other end of the header Q, a transverse diaphragm or partition Q' dividing the header Q into inlet and outlet sections. With this arrangement, the steam coming to the header Q passes 65 to the header R through the elements I con-

nected the latter to the portion of the header Q at the inlet side of the partition Q', and the steam then passes to the outlet section of the header Q through the remaining elements I. It is to be understood, however, that the present invention is not concerned with the number of passes for the steam which the elements I are arranged to form. When a header partition Q' is used, the adjacent elements I may well be spaced 70 apart and fire bricks W, or the like, placed between the spaced apart elements. It is not essential that the superheater should form the entire floor of the combustion chamber, and as shown, the superheater does 75 not extend clear to the front of the combustion chamber B, and the front wall of the latter is thickened to provide the corresponding portion of the combustion chamber floor. X represents drain connections 80 to the superheater headers Q and R.

A superheater constructed and located as described possesses the characteristic advantages of any ordinary furnace wall superheater in that it is an efficient superheater 85 and tends effectively to prevent combustion chamber wall overheating since all the vertical walls of the combustion chamber radiate heat to, and are cooled by the superheater.

With the superheater located in, or forming all or a large portion of the floor of the combustion chamber, I secure certain special advantages not obtained with a furnace wall superheater lining a vertical wall of the combustion chamber. For one thing the thermal expansion and contraction of the superheater floor elements need not subject the weight carrying side walls of the combustion chamber to any deforming or disturbing tendency. Furthermore, the location of the superheater relative to the points of fuel introduction, and the natural tendency of the hotter gases to rise, largely eliminates the tendency to injurious flame impingement frequently experienced with radiant superheaters located at the sides of combustion chambers in which jets of oil, gas or powdered coal are burned. The floor location of the superheater is of especial utility in a marine boiler because it eliminates all possibility of the boiler overheating the deck on which the boiler is located, and because it tends to a low center of gravity for the boiler as a whole, and because the floor of a marine boiler combustion chamber provides ample space, not always available in other walls, for the radiant heat superheater.

In a boiler furnace, the roof or side walls of which are composed of water tubes or other cooling devices, these cooling devices absorb heat by radiation, conduction and/or convection. The flame is interposed between the furnace floor and the water tubes

- and wall cooling devices, and in consequence the floor absorbs radiant heat at a rate tending to its rapid destruction, and the external heat radiation from the furnace floor is excessive. The application of a superheater in the floor of a boiler not only prevents this excessive heating of the floor, but allows the radiant heat of the gases to be absorbed both from the bottom as well as from the top and sides, which makes for high efficiency of the combined unit, and for a reduction in furnace temperature which eliminates some of the trouble experienced from slag choking up the lower boiler tubes. It also eliminates the heavy expense of furnace floors built of fire brick or other refractory materials.
- While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.
- Having now described my invention what I claim as new and desire to secure by Letters Patent is:—
1. The combination with a boiler furnace comprising a combustion chamber, of means for burning fuel in suspension in said chamber comprising a burner inlet in a vertical wall of said chamber, and a radiant heat superheater comprising horizontally disposed elements extending across said chamber at the bottom of the latter adjacent said vertical wall and adapted to absorb radiant heat at their upper sides from said chamber.
  2. The combination with a boiler furnace comprising a combustion chamber, of means for burning fuel in suspension in said chamber comprising a burner inlet in a vertical wall of said chamber, and a radiant heat superheater comprising horizontally disposed elements extending across said chamber at the bottom of the latter adjacent said vertical wall and having flattened upper sides which unite to form a continuous metallic floor for said combustion chamber adapted to absorb radiant heat from the latter.
  3. A boiler having a low center of gravity and limited headroom comprising a combustion chamber having front and rear vertical walls and a horizontal floor, a header mounted on the upper part of each of said walls, an inclined bank of tubes connecting said headers, means for burning fuel in suspension in said combustion chamber including a burner inlet in the lower part of said front wall adjacent said floor and a series of horizontal side by side superheater elements arranged in the floor of said combustion chamber and adapted to absorb radiant heat at their upper sides from said chamber.
  4. A marine boiler comprising a combustion chamber having front and rear vertical walls, a header mounted on each of said walls, a bank of tubes connecting said headers, means for burning fuel in suspension in said combustion chamber including a burner inlet in the lower part of said front wall and a series of horizontal side by side superheater elements arranged in the floor of said combustion chamber and adapted to absorb radiant heat from said chamber.
  5. In the combustion chamber of a marine boiler adapted for use in shallow draft vessels, the combination with means for burning fuel in suspension in said chamber comprising a fuel burner located in a vertical wall of said chamber, adjacent the lower end thereof, of a horizontal floor for said chamber adjacent said fuel burner comprising a plurality of horizontal thick walled superheater elements arranged side by side, said elements having flattened upper sides uniting to form a continuous metallic floor surface exposed to the radiant heat of said chamber, supporting means extending transversely of and connected to said superheater elements, a metallic sheathing extending below said elements, and heat insulating material between said elements and sheathing.
  6. In the combustion chamber of a marine boiler adapted for use in shallow draft vessels, the combination with means for burning fuel in suspension in said chamber comprising a fuel burner located in a vertical wall of said chamber adjacent the lower end thereof, of a horizontal floor for said chamber adjacent said fuel burner comprising a plurality of horizontal thick walled superheater elements arranged side by side and having flattened upper sides uniting to form a continuous metallic floor surface exposed to the radiant heat of said chamber and heat insulating material covering the lower sides of said elements, steam inlet and outlet headers located externally of said chamber, horizontal channels in the walls of said chamber adjacent the ends of said elements, conduits extending through said channels and connecting the ends of said elements to said headers, and yieldable heat insulating material positioned in said channels and surrounding said conduits.
- Signed at New York city, in the county of New York and State of New York, this 23rd day of April, A. D. 1926.
- JOSEPH JOHN NELIS.
